(57) **CLAIM**

The ornamental design for a collapsible crate, as shown and described.

DESCRIPTION

FIG. 1 is a perspective view of a collapsible crate;

FIG. 2 is a left-side view thereof;

FIG. 3 is a right-side view thereof;

FIG. 4 is a top view thereof;

FIG. 5 is a bottom view thereof;

FIG. 6 is a front view thereof; and,

FIG. 7 is a rear view thereof.

The dotted lines in the figures represent stitching and form part of the claimed design. The dotted and dashed lines in FIG. 5 represent crease lines and also form part of the claimed design.

1 Claim, 4 Drawing Sheets
